tion of Delaware

Application December 17, 1936, Serial No. 116,271

16 Claims. (Cl. 178—33)

This invention relates to printing telegraph apparatus, and particularly to selector mechanisms therefor.

An object of the invention is to increase the number of selective possibilities in a selector without increasing the time required for the performance of selections.

Another object of the invention is to provide compound adjustment of a pivotally mounted element of a selector mechanism.

The invention features various styles of detents for an element of a selector which is shiftable into either of two selective positions, and which may bounce considerably before settling into the selective positions.

It is well known that in the use of permutation code combinations of impulses for signalling, each additional impulse in the combination doubles the selective possibilities. Thus a five-unit code affords thirty-two usable selective combinations, and a six-unit code affords sixty-four usable selective combinations. In selector mechanisms such as those shown in Patent No. 1,745,633 granted February 4, 1930 to S. Morton et al., in Patent No. 1,917,308 granted July 11, 1933 to H. L. Krum, and in Patent No. 1,937,376 granted November 28, 1933 to W. J. Zenner, the selective possibilities may be increased by adding one complete set of those elements, including cam projections, selector sword levers, T-levers, etc., under the control of which notched permutation code bars are set. Thus a five-unit selector may be converted into a six-unit selector, a six-unit selector may be converted into a seven-unit selector, etc.

It should be remembered, however, that a selector mechanism thus converted requires an additional impulse in the signal combination to control the operation of the additional selector elements. If, in adding a code impulse to increase the selective possibilities, the same speed of operation in cycles or code combinations per unit of time is to be maintained, in order that the transmission of characters shall not be slower, and in order that special driving mechanisms need not be employed, the code impulses must be proportionally shortened, and the operation of each chain of elements controlling a code bar must be accelerated.

The present invention relates primarily to those features by means of which the selective possibilities of a selector mechanism are increased, while maintaining a given standard of operating efficiency, including the modification of the sword operating levers in a sword and T-lever selector

and the diminution of bounce in the selector lever by means of detents. The invention also contemplates a compound adjustment of the pivotal mounting of the selector lever.

For a full and complete description of the invention, reference may be had to the following detailed description, taken in connection with the accompanying drawings in which

Fig. 1 is a top plan view of one form of selector mechanism having applied thereto one form of selector lever detent;

Fig. 2 is a vertical sectional view taken approximately on the line 2—2 of Fig. 1;

Fig. 3 is a view partly in section showing a sword lever operating bell crank in relation to 15 its associated cam projection;

Fig. 4 is a plan view having a portion broken away and showing another form of selector mechanism which includes selector lever pivot adjusting means and another form of detent; 20

Fig. 5 is a perspective view of a portion of the selector mechanism shown in Fig. 4;

Fig. 6 is a vertical sectional view taken approximately on the line 6—6 of Fig. 4;

Fig. 7 is a detail view partly in section showing 25 the mounting of the detent shown in Figs. 4 and 5;

Fig. 8 is a fragmentary view showing still another form of detent;

Fig. 9 is a detail view partly in section showing 30 the mounting of the detent shown in Fig. 8; and

Fig. 10 is a fragmentary perspective view showing a modified selector lever bracket adjusting system.

Referring now to the drawings, in which identical reference characters designate corresponding parts throughout the several views, and particularly to Fig. 1, reference numeral 16 designates a mounting plate for the several elements constituting a selector mechanism intended, primarily, for printing telegraph apparatus. A bracket 17 secured to plate 16 by means of bolts 18 supports laminated core 19 of selector magnet 21 which includes pole face 22. Mounting plate 16 also supports bracket 23 which has a pivotal mounting 24 for selector lever 26 which has rigidly secured thereto selector magnet armature 27. Tension spring 28 has one end secured to armature 27 and the other end engaging tension adjusting screw 29, whereby armature 27 and selector lever 26 are biased to their extreme clockwise position, in which position armature 27 is in its retracted position corresponding to the deenergized condition of the selector magnet.

At its outer or free end, selector lever 26 is 55

provided with spaced depending arms 31 (Fig. 2). Depending arms 31 are arranged to control the setting of the thin, flat, selector levers contained in a sword and T-lever selector mechanism designated generally by the reference numeral 32. Selector mechanism 32 includes a plurality of separator plates 33 secured one above the other in spaced relation upon a plurality of studs 34 carried by mounting plate 16. Between each two of the separator plates 33 there is disposed a thin, flat, selector finger or sword lever 36 arranged to undergo pivotal and reciprocatory movement. At its left-hand end, as viewed in Fig. 1, each of the sword levers 36 is provided with a disc-like portion 37 which is retained in a correspondingly shaped aperture in a thin, flat, bell crank lever 38 pivotally mounted on pivot pin 39 and urged in clockwise direction by tension spring 41 connected to spring post 42. At its outer or right-hand end, as viewed in Fig. 1, each sword lever 36 is pointed and abuts one of a plurality of T-levers 43 pivotally mounted on pivot pin 44 and having outwardly extending arms 46 terminating in disc-like portions 47 through which T-levers 43 are adapted to be articulated to code discs or code bars not shown. Adjacent to its disc-like portion 37 each of the sword levers 36 is provided with oppositely extending arms 48 which terminate in abutments 49. The abutments 49 are spaced apart a distance slightly greater than the distance between the depending arms 31 of selector lever 26 so that when lever 26 is in its extreme clockwise position, which it occupies when selector magnet 21 is deenergized, one of its arms 31 is in alignment with one set of abutments 49 of sword levers 36, and when the selector lever 26 is in its extreme counterclockwise position, its other depending arm 31 is in alignment with the other set of abutments 49.

As shown in Fig. 2, a power-driven shaft 51 extends through an aperture in mounting plate 16 and has secured thereto spaced discs 52 and 53. Above and below discs 52 and 53 respectively are friction discs 54 of resilient material which frictionally engage end discs 56 rigidly secured to a selector cam assembly 57. Cam assembly 57 includes cam projections 58 equal in number to the number of impulses of a code combination on which the selector mechanism is adapted to be operated, and, therefore, equal in number to the T-levers 43. The cam projections 58 are arranged helically around the cam assembly 57 and each cam projection is aligned with one of the bell crank levers 38. Cam assembly 57 includes a cam 59 with which there is aligned the follower portion 61 of a selector lever locking bell crank 62 which is pivotally mounted upon pivot pin 39 and is urged in counterclockwise direction to bring its follower portion 61 into engagement with cam 59 by tension spring 63. Locking bell crank 62 terminates in a locking projection 65 which occupies blocking position with respect to an abutment 64 of a selector lever 26 when follower portion 61 rests against one of the nadir portions of cam 59.

Cam assembly 57 includes a stop arm 66 which has at its outer end upstanding arm 67. Above cam assembly 57 there is fixedly mounted on posts 68, carried by mounting plate 16, a plate 71 which carries pivotally mounted thereon coaxially with the shaft 51 a plate 72 on which is pivotally mounted a stop gate 73 which has a portion disposed in the path of upstanding arm 67 of cam assembly stop arm 66. A stop gate latching lever 74 has a shoulder portion capable of

locking stop gate 73 in position to arrest stop arm 66, and a compression spring 76 urges lever 74 into engagement with stop gate 73. A bell crank lever 77 pivotally mounted on bracket 78 carried by the rigidly mounted plate 71 has one arm in operative engagement with locking lever 74 at a point coaxial with the pivotal mounting of plate 72 and with shaft 51. The other arm of bell crank 77 is aligned with a plunger pin 79 with which there cooperates an abutment screw 10 81 carried by arm 82 rigidly connected to selector lever 26 and armature 27. The shank of screw 81 is eccentric with respect to the head thereof so that operative relationship between arm 82 rigid with selector lever 26 and plunger pin 79 15 may be adjusted as desired.

Plate 72 is mounted below plate 71 as indicated in Fig. 2. There is an arm 83 pivoted on plate 71 above said plate and coaxially with pivot plate 72, and knurled locking screw 84 20 passes through arm 83 and threadedly engages plate 72, whereby the latter plate may be clamped in any desired position with respect to fixed plate 71.

Referring again to Fig. 1, it will be noted that selector lever 26 carries an upstanding abutment pin 86 which in the particular embodiment is cylindrical. An arm 87 pivotally mounted at 88 to bracket 89 has at its outer end a disc-like portion 91 which is held in engagement with abutment pin 86 by tension spring 92 which has one end engaging arm 87 and the other end engaging bracket 89. Pivotally mounted arm 87 serves as a detent to reduce bounce in the operation of selector lever 26 as will be described hereinafter.

In operation, shaft 51 is continuously rotated and a continuous torque is applied to cam assembly 57 through friction discs 54. The selector magnet 21 is connected with a telegraph line and in a start-stop system of operation the line 40 has current flowing therein when the circuit is idle but conditioned for the transmission of a message, whereby selector magnet 21 is energized and armature 27 is attracted to pole face 22 as indicated in Fig. 1. With the armature attracted, selector lever 26 is in its extreme counterclockwise position and plunger pin 79 is in its retracted position, whereby the shoulder of lever 74 is permitted to engage the stop gate 73, which, in turn, restrains the cam assembly 57 45 from rotating. The first impulse of any code combination which is applied to the telegraph line is the start impulse, which is usually represented by a no-current condition on the telegraph line. The start pulse thus results in the deenergization of selector magnet 21 and permits armature 27 to be retracted by spring 28, whereby selector lever 26 is shifted to its extreme clockwise position, causing plunger 79 to be depressed. Bell crank lever 77 is thus rocked counterclockwise 60 (as viewed in Fig. 2), and lever 74 is rocked clockwise to lift its shoulder out of engagement with stop gate 73. The stop gate thus being permitted to rock, cam assembly 57 responds to the torque applied by shaft 51 and escapes by rocking stop 65 gate 73.

As cam assembly 57 rotates, cam 59 withdraws locking bell crank 62 from locking engagement with abutment 64 in timed relation to the signal impulses applied to selector magnet 21, whereby 70 armature 27 is permitted to respond to conditions of energization and deenergization of magnet 21 and selector lever 26 is shifted into its clockwise or counterclockwise position in accordance with the signal impulses. Cam projections 75

58 rock the sword lever bell cranks 38 counterclockwise successively and in timed relation to the signal impulses so that sword levers 36 are drawn leftwardly (as viewed in Fig. 1). As each sword lever is thus moved leftwardly, one or the other of its abutments 49 is brought into engagement with one or the other of arms 31 of selector lever 26, and those sword levers which encounter one of the arms 31 before they reach the limit of 10 their leftward travel are rocked clockwise or counterclockwise, depending upon the position in which selector lever 26 is presented. Thus, the sword levers are set in permutative arrangement in accordance with signal impulses applied to the 15 selector magnet, and since each sword lever controls one of the T-levers 43, and may encounter the T-lever on either side of its pivot 44, the T-levers are set in permutative arrangement corresponding to the sword levers 36 and in turn position the code discs or code bars to which they 20 are articulated.

The final impulse in a signal combination is a stop pulse, which is ordinarily represented by current on the telegraph line and so results in energization of selector magnet 21 and attraction of its armature 22. Plunger pin 79 is thus permitted to move to its retracted position and lever 74 is presented in locking engagement with stop gate 73, these conditions being effected by compression spring 76. Stop gate 73 thus being locked arrests stop arm 66 and cam assembly 57 at the conclusion of one revolution and the selector magnet is thus conditioned for reception of the next code signal combination. In such stop 35 condition, the locking bell crank lever 62 engages a high portion of cam 59 and is thus held out of blocking engagement with abutment 64 so that selector lever 26 is capable of responding to a start pulse applied to the selector magnet.

40 As previously set forth, it is desirable not to reduce the operating speed of a selector mechanism and associated printing telegraph apparatus when such selector mechanism is converted to increase the selective possibilities, as from five-unit to six-unit code operation. It is desirable to maintain standard operating speed in order that the efficiency of the telegraph line shall not be diminished and also in order that standard driving mechanism may be employed. Thus, it will be desirable to operate shaft 51 at the same velocity regardless of whether the selector mechanism is to position five or six code bars or discs, but if a five-unit code is employed, five sword levers will be set permutatively during one revolution of cam assembly 57, whereas, if a six-unit code is employed, six sword levers 36 will need to be conditioned permutatively in the same time interval. Under such circumstances, the interval of time in which the selector lever 26 may be set and the bell crank lever 38 rocked counterclockwise to draw sword lever 36 leftwardly, will be shorter in six-unit code operation than in five-unit code operation. One of the methods by which the time interval for one sword lever operating cycle may be reduced is to accelerate the operation of sword lever operating bell crank 38. This may be accomplished in the manner shown in Fig. 3. It will be noted that the time required to operate a bell crank 38 will be dependent upon 55 the point at which cam projection 58 engages lever 38 and that as the curvature of lever 38 at the point of engagement is altered and made more concave, as indicated in dotted lines in Fig. 3, cam projection 58 will engage lever 38 later than it would with the curve as indicated in

solid lines and will be in engagement with lever 38 for a shorter period of time so that bell crank 38 will be moved to its counterclockwise position more rapidly and therefore the setting of the associated sword lever will be consummated in a 5 shorter period of time.

It is essential that the selector lever 26 be brought substantially into rest position and locked in that position by the locking bell crank lever 62 before an abutment 49 of one of the sword 10 levers 36 is brought into engagement with one of the arms 31 of selector lever 26 by operation of the associated bell crank lever 38. Accordingly, it has been found desirable to bring about some of the reduction in the operating cycle of a 15 sword lever in the setting of the selector lever 26 rather than to attempt to accomplish all of such reduction in the operation of the sword lever operating bell crank 38.

The response of armature 27 to energized condition of selector magnet 21 is relatively violent and thus selector lever 26 may vibrate or bounce before coming to rest in its extreme counterclockwise position. Similarly, spring 28 is relatively violent in the rocking of selector lever 26 25 clockwise and the lever tends to vibrate before coming to rest in its extreme clockwise position. Locking bell crank 62 cannot be brought into blocking relation with abutment 64 until the vibration of selector lever 26 has been reduced to 30 very small amplitude and a sword lever 36 can- 35 not be moved leftwardly until selector lever 26 has been locked. More immediate locking of the selector lever in each sword lever operating cycle is thus dependent upon reduction of bounce of the selector lever and this may be accomplished by means of the previously described detent lever 87 cooperating with upstanding abutment pin 86. As selector lever 26 passes from one of its extreme positions to the other, abutment pin 86 40 moves across the surface of disc-like portion 91 and rocks detent lever 87 clockwise against the tension of spring 92. When detent lever 87 reaches its extreme clockwise position, abutment pin 86 passes over the outermost portion of disc 45 91 and engages a descending arc, whereupon spring 92 adds its effect to the force which is moving selector lever 26 to bring that lever into rest position, and little or no bounce occurs due to the detent action of lever arm 87. With this 50 arrangement the selector lever 26 may be blocked by locking bell crank 62 much earlier in a sword lever operating cycle than is possible without the detent lever.

The cylindrical abutment pin 86 and cooperating disc-like portion 91 of detent arm 87 were found to be particularly effective in the type of selector mechanism shown in Figs. 1 and 2. The cooperating surfaces of the two elements have constantly changing slopes and the change is 60 such that the force required to be exerted by the selector lever to rotate the detent lever 87 against the tension of spring 92 is a maximum as selector lever 26 begins to move and decreases until it comes to zero when the detent has been 65 brought to its extreme clockwise position. Thereafter detent 87 exerts a continuously increasing force upon a selector lever to bring it to rest in the selective position.

The anti-bounce detent, disclosed in Figs. 1 and 70 2, is a permissive detent in that it does not positively stop selector lever 26 in either of its extreme positions. Selector magnet 21 exerts a force upon armature 27 tending to move the armature into engagement with pole face 22, and 75

if any positive stop is employed near the free end of selector lever 26, that lever may become twisted or otherwise deformed, or even broken due to the arrestment of the selector lever before armature 27 has come to rest. Accordingly, it is desirable to apply any limiting stops which may be employed to armature 27 and provide no positive stops to selector lever 26. Locking bell crank 62 is not to be considered as a positive stop because it does not come into blocking relation with selector lever 26 until after that lever has been brought substantially to rest.

Referring now to Figs. 4 and 5, there is shown a modified form of selector mechanism similar to that shown in the hereinbefore mentioned Zenner patent in which the selector lever is controlled in accordance with the attraction or non-attraction of the selector magnet armature without being connected directly to the armature. In Figs. 4 and 5, reference numeral 101 designates a mounting plate upon which is pivotally mounted bracket 102 which supports core member 103 of selector magnet 104. Bracket 102 is pivotally mounted on plate 101 by means of pivot screw 105 and its alignment with respect to plate 101 is adjustable by rotation of screw 106, which, having spaced head and flange between which stud 107 carried by plate 101 is disposed, is incapable of axial movement and therefore imposes movement to bracket 102 which it threadedly engages. Clamping screws 108 extend through arcuate slots in bracket 102 and threadedly engage mounting plate 101, whereby bracket 102 may be rigidly clamped in desired position to mounting plate 101.

A bell crank lever, which comprises arms 111 and 112, and which is commonly identified as an armature lever, is pivotally supported by screw 105 and by coaxially mounted pivot screw 113 carried by bracket 102. Armature 114 of selector magnet 104 is rigidly secured to arm 112 of the armature lever. The free end of lever arm 111 terminates in a cam follower portion 116 which is adapted to engage an armature cam (not shown).

Mounting plate 101 supports a sword lever and T-lever assembly 118 similar to assembly 32 of Fig. 1, and similarly including sword levers 119 and T-levers 121. The sword levers 119 are provided with abutments 122 for cooperation with spaced depending arms 123 of a selector lever 124. Selector lever 124 is pivotally mounted by means of pivot screws 126 on a bracket 127, which is adjustably secured to mounting plate 101 in a manner which will be described hereinafter. Selector lever 124 has connected to it one end of a tension spring 128, the other end of which is connected to extension 129 of arm 111 of the armature lever. An abutment screw 131 also carried by extension 129 has its head in engagement with selector lever 124 to maintain spring 128 under tension and to serve as a positive drive between the armature lever and the selector lever in one direction. A locking lug 132 carried by selector lever 124 at the free end thereof cooperates with a locking blade 133 of locking bell crank lever 134 pivotally mounted on the pivot pin 136 to lock the selector lever in either of its two selective positions. Locking bell crank lever 134 is actuated to unlock and relock selector lever 124 in timed relation to signals applied to selector magnet 104 similarly to previously described locking bell crank 62, by a cam similar to cam 59. A plate 137 similar to plate 71 carries a stop gate (not shown) for the arrestment of a selector cam

assembly (not shown) and the stop gate mechanism includes a plunger pin 138 similar to plunger pin 79 which is controlled by an abutment screw 130 carried by extension 129 of flutter lever arm 111. Clamping arm 141 and clamping screw 142 are provided for clamping the stop gate in any desired position of adjustability with respect to plate 137.

The previously described bracket 127, which pivotally mounts selector lever 124, is provided with clearance holes 146 through which extend clamping screws 147 threadedly engaging mounting plate 101, and by means of which bracket 127 may be clamped in desired position. Intermediate the clearance holes 147, bracket 127 is provided with elongated slot 148 in which is disposed head 149 of an adjusting screw which has its shank eccentric with respect to the head and extending through an aperture in the mounting plate 101. At the end, opposite from the point at which pivot screws 126 are mounted, bracket 127 is provided with a cylindrical aperture into which is fitted the head 151 of an adjusting screw which has eccentric shank 152 extending through an aperture in mounting plate 101. When screws 147 are loosened, the pivotal mounting of selector lever 124 may be moved in an arc, which has its center on the axis of adjusting screw head 151, by rotating adjusting screw head 149 in slot 148. The effect of this adjustment is to vary the distance between depending arms 123 of the selector lever and abutments 122 of sword levers 119. The pivotal mounting of lever 124 may be adjusted in a transverse direction by rotating screw head 151 which causes mounting bracket 127 to shift longitudinally while being guided by adjusting screw head 149 within slot 148.

An anti-bounce detent lever 156 is adjustably mounted upon eccentric bushing 157 (Fig. 7) carried by post 158 which is supported by mounting plate 101. A clamping screw 159 clamps bushing 157 in any desired position of adjustment while permitting detent lever 156 to rotate thereon. Detent lever arm 156 is provided near its free end with an open aperture 161, at the base of which is a crown or ridge 162 from which oppositely sloping surfaces extend and intersect the sides. An abutment pin 163 is mounted on the selector lever 124 and is disposed within the aperture 161 in detent lever 156. A tension spring 164 biases detent arm 156 in clockwise direction to bring the base of its aperture into engagement with abutment pin 163.

It will be noted that in the selector mechanism shown in Fig. 4, the armature lever may be rotated into its extreme counterclockwise position so that armature 114 engages the pole face of selector magnet 104 without selector lever 124 being simultaneously correspondingly positioned, and that the selector lever will become correspondingly positioned when permitted to move by withdrawal of locking blade 133 from blocking alignment with locking lug 132. It will also be observed that when selector lever 124 is in its extreme counterclockwise position and the armature lever attempts to rotate to its extreme clockwise position, it will be prevented from rotating due to engagement of abutment screw 131 with selector lever 124, until locking blade 133 unlocks the selector lever.

The first impulse of a signal combination is, as previously described, a start impulse, which results in deenergization of selector magnet 104, whereupon armature 114, being no longer held,

may be drawn away from the pole face by the armature lever which rotates to its extreme clockwise position. Plunger pin 138 is thus depressed to release the stop gate (not shown) to permit 5 rotation of the selector cam assembly (not shown). As the selector cam assembly rotates, it cyclically rotates the armature lever to bring armature 114 into engagement with its pole face, it cyclically unlocks selector lever 124 and it 10 successively actuates the several sword lever operating bell cranks. When the armature 114 is held by magnet 104, after being rocked into engagement with its pole face, abutment screw 131 is drawn away from selector lever 124, and it 15 when locking bell crank 134 unlocks the selector lever, it rotates into its extreme counterclockwise position. When the selector magnet 104 is deenergized, armature 114 is not held and the armature lever returns, or tends to return to its 20 extreme clockwise position, whereupon the selector lever, if then in its extreme counterclockwise position, moves to its extreme clockwise position when unlocked by the locking lever 134. In this manner the selector lever is positioned 25 selectively and sword levers 119 and T-levers 121, are positioned permutatively in accordance with signal impulses applied to selector magnet 104. Since the selector lever is not directly connected to the selector magnet armature 114, it may lag 30 behind the armature in its operation, under the control of the lock lever 134. The interconnection between armature 114 and selector lever 124 being non-rigid, as distinguished from the structure shown in Fig. 1, the detent arm 161 may 35 include positive stops since there is no possibility of injury to the selector lever as a result of violent operation of the armature lever or selector magnet armature. Accordingly, the aperture in the detent lever 156, in which abutment pin 163 is 40 disposed, affords the positive stops comprising its opposite sides, and also affords the camming surfaces comprising the oppositely sloping surfaces intersecting in the central ridge 162. When the selector lever 124 shifts from one to another 45 of its rest positions, the abutment pin 163 cams detent arm 156 to rotate in clockwise direction in opposition to tension spring 164 until ridge 162 is passed, whereupon spring 164 assists in bringing the selector lever into its rest position, 50 and any tendency of the selector lever to bounce is quickly eliminated.

In Figs. 8 and 9, there is shown another form of detent which may be employed for reducing 55 bounce in selector levers of the type shown in Fig. 4, which are not rigidly connected to the selector magnet armature. This detent is designated by the reference numeral 171, and may be mounted on the eccentric bushing 157 supported by post 158, as shown in Fig. 9. Clamping screw 159 maintains bushing 157 in the desired fixed position with respect to post 158 after it has been adjusted. Detent lever 171 is provided with a closed aperture of arcuate shape which is entered by detent pin 173 carried by 60 selector lever 124. A tension spring 174 urges detent 171 in counterclockwise direction, whereby by detent pin 173 is cammed into abutment with one or the other of the ends of arcuate aperture 172.

70 In operation, detent arm 171 is rotated clockwise as selector lever 124 shifts from one of its positions to the other and the tension in spring 174 is increased during such rotation. As pin 173 passes the midpoint of arcuate aperture 172, 75 it adds to the restoring effect of spring 174 an

additional driving force by engaging the right-hand wall of aperture 172, as viewed in Fig. 8, and thus positively drives detent arm 171 into such position that pin 173 may come to rest at the end of the arcuate aperture. Any substantial 5 tendency of selector lever 124 to bounce is resisted by the left-hand cam surface of the arcuate aperture 172 in detent arm 171.

It will be noted that detent 171 embodies positive stops for selector lever 124 as in the case 10 of detent 156 shown in Figs. 4, 5, and 7. Detent 171 has the additional characteristic of aiding its restoration spring in returning it to normal position, which characteristic detent 156 does not possess due to the fact that the aperture 15 therein is open at one side.

Detent 171 is shown as positioned below selector lever 124 with pin 173 extending downwardly from the selector lever. It will be understood that this detent is capable of being mounted 20 above the selector lever to cooperate with a detent pin upstanding therefrom, and that detent 156 could, with equal facility, be positioned below the selector lever, if desired.

In Fig. 10 there is shown a modified arrangement for adjusting the bracket which pivotally supports the selector lever in a selector mechanism of the type shown in Fig. 4. The principal difference between the adjusting arrangements is that in the structure shown in Fig. 10, the 30 means by which the selector lever is shifted longitudinally is not a permanent part of the selector mechanism. It will be noted, in Fig. 10, that the mounting plate 101 supports a selector lever bracket 181 which has clearance holes 182 35 through which extend the shanks 183 of clamping screws similar to clamping screws 141 of Figs. 4 and 6 and similar threadedly engaging mounting plate 101. Bracket 181 is pivotally mounted on the cylindrical head of screw 184 40 which may be an eccentric adjusting screw similar to screw 151 (Figs. 4, 5, and 6).

On opposite sides of bracket 181, mounting plate 101 is provided with cylindrical apertures 186. For adjusting bracket 181 angularly about mounting screw 184, there is provided a tool, the shank 187 of which is provided with an eccentric projection 188 of lesser diameter than shank 187 and dimensioned to enter freely either of the apertures 186 in mounting plate 101. Eccentric projection 188 is adapted to enter one of the apertures 186, after which shank 187 may be rotated. Projection 188 will then define the center of rotation, and shank 187 constitutes an eccentric which, coming into engagement with bracket 181, and the rotation being continued, will shift bracket 181 angularly about the head of screw 184. The direction of movement of bracket 181 is determined by the particular one of apertures 186 into which the eccentric tool is 50 fitted. With this arrangement, the positioning of bracket 181 may be accurately controlled, after which the bracket may be positively retained in the desired position by means of the clamping screws which extend through the clearance apertures 183.

Although specific embodiments of the invention have been shown herein, it will be understood that the invention is capable of modification, rearrangement, and substitution within the 70 scope of the appended claims.

What is claimed is:

1. In a selector mechanism, signal responsive means, a selector element presentable in either of two positions under control of said means,

means for operatively supporting said selector element, means for imparting movement of one character to said supporting means, and means for imparting movement of another character 5 to said supporting means.

2. In a selector mechanism, signal responsive means, a selector element presentable in either of two positions under control of said means, means for operatively supporting said selector 10 element, means for imparting compound movement to said supporting means, and means for clamping said supporting means to resist such movement.

3. In a selector mechanism, signal responsive 15 means, a selector element movable to either of two selective positions under control of said means, means for pivotally supporting said selector element having a circular aperture and an elongated aperture therein, and means comprising eccentrics disposed within said apertures for imparting compound movement to said supporting means.

4. In a selector mechanism, signal responsive 20 means, a selector element presentable in either of two selective positions under control of said means, means for pivotally supporting said selector element having a circular aperture and an elongated aperture therein, and eccentric means disposed within said apertures for shifting the 25 pivotal axis of said selector element longitudinally and transversely of said element.

5. In a selector mechanism, signal responsive 30 means, a selector element presentable in either of two selective positions under control of said means, a bracket having pivotal means for supporting said element, said bracket having a circular aperture and an oblong aperture therein, a rotational member having an eccentric portion disposed within said circular aperture in substantially close-fitting relation therewith, and a rotational member having an eccentric portion disposed within said oblong aperture in substantially 35 close-fitting relation with the sides thereof only.

45 6. In a selector mechanism, signal responsive means, a selector element presentable in either of two selective positions under control of said means, a bracket having at one end thereof means for pivotally supporting said element, said bracket having a circular aperture at the other end thereof and an elongated aperture intermediate the ends, a rotational member having an eccentric portion disposed within said circular aperture in substantially close-fitting relation 50 therewith, and a rotational member having an eccentric portion disposed within said elongated aperture in substantially close-fitting relation 55 with the sides thereof only.

7. In a selector mechanism, a mounting plate, 60 signal responsive means carried by said mounting plate, a bracket having clearance apertures carried by said mounting plate, clamping means extending through said clearance apertures and threadedly engaging said mounting plate, a selector element pivotally supported by said bracket and presented in either of two selective positions 65 under control of said signal responsive means, said bracket having a circular aperture and an elongated aperture therein, a member rotationally supported by said mounting plate and having a cylindrical eccentric portion disposed within 70 said circular aperture in close-fitting engagement therewith, and another member rotationally supported by said mounting plate and having a cylindrical portion disposed within said 75

elongated aperture in close-fitting engagement with the sides thereof only.

8. In a selector mechanism, a selector element 5 presented in either of two selective positions, signal responsive means for controlling the presentation of said selector element in said positions, and means for overcoming reactive forces opposing the presentation of said element in said selective positions including positive stops for said selector element.

9. In a selector mechanism, a selector element 10 mounted for pivotal movement into either of two selective positions, signal controlled means for effecting the presentation of said element in said 15 positions, an abutment pin carried by said selector element, and a pivotally mounted spring biased detent arm having a portion operatively engageable with said pin for overcoming reactive forces tending to postpone the arrival of said element at rest condition in said selective positions. 20

10. In a selector mechanism, a selector element 25 pivotally mounted for presentation in either of two selective positions, signal controlled means for effecting the presentation of said element in said positions, a cylindrical abutment pin carried 30 by said selector element, and a pivotally mounted spring biased detent arm having a disc-like portion maintained in surface engagement with said abutment pin.

11. In a selector mechanism, a selector element 35 pivotally mounted for presentation in either of two selective positions, signal controlled means for effecting the presentation of said element in said positions, an abutment pin carried by said selector element, a pivotally mounted spring 40 biased detent having an open aperture in which said abutment pin is disposed, said aperture having substantially parallel sides forming positive stops for said selector element, and oppositely sloping cam surfaces at the base thereof for resisting reactive forces postponing the arrival of 45 said selector element at rest condition in either of said positions.

12. In a selector mechanism, a selector element 50 pivotally mounted for presentation in either of two selective positions, signal controlled means for effecting the selective presentation of said element in said positions, an abutment pin carried by said selector element, a pivotally mounted and spring biased detent arm having an enclosed 55 aperture in which said abutment pin is disposed, said aperture affording positive stops for said selector element, said aperture also affording an arcuate surface with which said abutment pin cooperates to expedite restoration of said detent 60 arm to normal position, and said aperture also affording oppositely sloping cam surfaces with which said abutment pin cooperates to oppose the active forces tending to postpone the arrival of 65 said selector element at rest condition in said selective positions.

13. In a selector mechanism, a selector element 70 pivotally mounted for presentation in either of two selective positions, signal controlled means for effecting the presentation of said element in said selective positions, an abutment pin carried by said selector element, a pivotally mounted detent arm having an aperture in which said abutment pin is disposed, means for shifting the pivotal axis of said detent arm, and means 75 for clamping said shifting means in any effective position thereof.

14. In a selector mechanism, a mounting plate, a bracket adjustably supported by said plate, a selector element pivotally supported by said 75

EDWIN W. F. HANKE.

- bracket and adapted to be presented in either of two selective positions, signal controlled means supported by said plate for effecting the presentation of said element in said selective positions,
- 5 a locking lug carried by said selector element at a point spaced from the pivotal mounting thereof, a pivotally mounted lock lever cooperating with said lug to block said selector element in either of its selective positions, a pivotally mounted
- 10 detent arm cooperating with said selector element and affording positive stops therefor, and means for adjusting the pivotal mounting of said detent arm in accordance with the adjustment of said bracket.
- 15 15. In a selector mechanism, signal responsive means, a selector element presented in either of two selective positions under control of said sig-

nal responsive means, means for pivotally supporting said selector element, means for pivotally supporting said supporting means, and eccentric means for controlling the pivotal position of the last mentioned means.

16. In cooperation with a selector mechanism including a foundation member having a circular aperture therein and adjustably mounted thereon an element pivotally supporting selector means, a manually operable tool for adjusting said element including a cylindrical portion dimensioned to enter said aperture and be rotationally guided thereby, and another cylindrical portion eccentric to the first mentioned cylindrical portion adapted to engage and effect adjustment of said selector means supporting element.
